UNITED STATES PATENT OFFICE.

JOHN H. WILKINS, OF WASHINGTON, DISTRICT OF COLUMBIA.

DESIGN FOR A BAG FOR CONTAINING MERCHANDISE.

53,723.

Specification for Design.

Patented Aug. 19, 1919.

Application filed March 26, 1918. Serial No. 224,909. Term of patent 14 years.

To all whom it may concern:

Be it known that I, JOHN H. WILKINS, a citizen of the United States, residing at Washington, in the District of Columbia, have invented a new, original, and ornamental Design for a Bag for Containing Merchandise, of which the following is a specification, reference being had to the accompanying drawing, forming a part thereof.

Copies of this patent may be obtained for five cents each, by addressing the "Commissioner of Patents, Washington, D. C."

Fig. 2 is a perspective view looking at the bag in the opposite direction, showing my new design.

I claim:

The ornamental design for a bag for containing merchandise, as shown.

JOHN H. WILKINS.
